UNITED STATES PATENT OFFICE.

JOHN A. LIEB, OF NEWARK, NEW JERSEY.

CIGAR-TIP CUTTER.

SPECIFICATION forming part of Letters Patent No. 242,340, dated May 31, 1881.

Application filed March 14, 1881. (No model.)

To all whom it may concern:

Be it known that I, JOHN A. LIEB, a citizen of the United States, residing at Newark, in the county of Essex and State of New Jersey, 5 have invented new and useful Improvements in Cigar-Tip Cutters, of which the following is a specification.

This invention consists in a cigar-tip cutter composed of four knives which are pivoted together at their ends in the form of lazy-tongs, and two handles which extend from the ends of two of the knives and are exposed to the action of a spring, which has a tendency to force the handles apart and to keep the knives open 10 for the introduction of the tip of a cigar.

My invention is illustrated in the accompanying drawings, in which Figure 1 represents a plan or top view. Fig. 2 is a longitudinal section in the plane xx , Fig. 1.

Similar letters indicate corresponding parts.

In the drawings, the letter A designates my cigar-tip cutter, which consists of four knives, a b c d , which are connected together by pivots d' e' f g in the form of lazy-tongs. The inner edges of the two knives b d are beveled or sharpened downward, as shown in the drawings, while the inner edges of the knives a and c are beveled or sharpened upward, so that when the four knives are connected their cutting-edges work closely against each other.

From the ends of the knives a and b extend the handles h and i , and to each of these handles is secured a spring, j , the loose ends of

which bear against each other, so that the two springs combined practically form one spring, 35 which has a tendency to force the handles apart and to throw the knives open, as shown in Fig. 1 of the drawings, leaving a space, k , between the cutting-edges of said knives for the reception of the tip of a cigar.

When the handles are compressed against the action of their spring or springs, the cutting-edges of all the knives move toward the center of the opening k with a drawing cut or shear cut, and the tip of the cigar previously 45 placed into said opening is cut simultaneously from four sides, so that a clean cut is produced, and the cigar, even if the same should be very dry, is not liable to become broken or injured.

What I claim as new, and desire to secure by 50 Letters Patent, is—

As a new article of manufacture, a cigar-tip cutter composed of four knives connected together in the manner of lazy-tongs, two handles extending from the ends of two of the 55 knives, and a spring or springs for forcing the handles apart and throwing the knives open, substantially as shown and described.

In testimony whereof I have hereunto set my hand and seal in the presence of two sub- 60 scribing witnesses.

JOHN A. LIEB. [L. S.]
